Atty's:

UNITED STATES PATENT OFFICE.

THOMAS H. KANE, OF YOUNGSTOWN, OHIO, ASSIGNOR TO TRUSSSED CONCRETE STEEL COMPANY, OF DETROIT, MICHIGAN, A CORPORATION OF MICHIGAN.

WINDOW.

1,235,979.

Specification of Letters Patent.

Patented Aug. 7, 1917.

Application filed March 25, 1915. Serial No. 16,874.

To all whom it may concern:

Be it known that I, THOMAS H. KANE, a citizen of the United States, residing at Youngstown, in the county of Mahoning and State of Ohio, have invented a new and useful Window, of which the following is a specification.

This invention relates to a window including mutually counterbalancing sashes, and one of its objects is to provide a construction wherein considerable ventilation may be obtained at the meeting rails without creating a draft at the sill level. For this purpose a pair of connected sashes are employed, one 15 of which has a combined sliding and swinging movement, the other being arranged to slide in a vertical plane. Other objects of the invention are to provide means for so controlling the movement of the first mentioned sash that it is caused to assume a position parallel to the other sash after being moved a predetermined distance; to provide means for sealing the joint between the sash that has the combined movement and the 20 frame; to provide means for conveniently securing the sealing means in position; to provide a tight joint between the meeting rails of the sashes; to provide a device in which the usual screens and awnings may 25 be used; and to improve the construction of the window generally.

The nature of the invention will be more fully understood from the description and drawings, wherein one embodiment of my 30 invention is shown, and in the latter of which Figure 1 is a vertical section of the window. Fig. 2 is a fragmentary view from the inside, parts being broken away. Fig. 3 is a 35 diagrammatic section on the line 3—3 of Fig. 5 showing the window partly open. Fig. 4 is a similar section, the window being 40 entirely open. Fig. 5 is a horizontal section through the lower sash and adjacent parts.

Similar reference characters refer to like 45 elements throughout the several views.

For convenience, the outside of the window or building will be termed the "forward" side and the inside, the "rear"; while those portions of the frame that project into 50 the window opening will be said to extend "inwardly."

In the embodiment of my invention shown, the main side members are formed of rolled I-sections 1 having flanges 2 inclined inwardly toward the central plane of the win-

dow. The upper ends of the main members are joined by the top plate 3 comprising an edge flange 4 and an intermediate flange 5, the latter being shouldered at 6; and a sill plate, similar in cross-section and reversely 60 arranged, connects their lower ends. These elements are disclosed in my United States application for patent filed January 8th, 1915, Serial Number 1087; and, while desirable in the present construction, may be 65 replaced by sections of other forms. The upper rail 8 and side bars 9 of the upper sash, together with the guide strips 10 therefor, and the wedge strips by which the guides are thrust sidewise and clamped in 70 position, may be of the same cross-section as those shown in the above mentioned application, or other desired members may be used in their stead.

It will be noted that the wedge strip 75 comprises a forward flange 12 and a rear flange 13 that are joined to a body portion 14 by inclined shoulders 15, and that the whole strip is adjustable toward the sash by screws 16. If desired, the rear flange may be removed from a point at about the level of the meeting rails upwardly, as shown in Fig. 1; and the extreme upper ends of both wedge and guide strips may be cut away at 18 to 80 allow the attachment of a bracket 19, upon 85 which a counterbalance pulley 20 is carried, directly to the main side member 1.

Supported upon the rear portion of the side members in each instance is a combined 90 guide and sealing member, substantially U-shaped in cross-section, one flange 22 preferably being beveled on its rear edge and having a beveled rib 23 along its forward edge, whereby the whole member may be wedged into and retained in position against 95 the flange 2 by simply adjusting the screws 16. The same action, it will also be observed, secures the guide strip 10 for the forward sash in place (Fig. 5). The other flange 25 of the guide and sealing member is 100 embraced by the U-shaped side bar 26 of the lower sash, whereby a tight joint is formed when the window is closed; and, for the same purpose, the upper rail 27 of the lower sash is provided with the vertical flange 28 105 (Fig. 1) that terminates in a horizontal flange 29, and with a second horizontal flange 30 spaced a distance from the flange 29 substantially equal to the thickness of a rearwardly extending rib or flange 31 on the 110

lower rail 32 of the upper sash. As shown, the flange 30 is one leg of an angle iron 33 riveted to the vertical flange 28.

The lower rail of the lower sash has on each side a bracket 35, from each of which projects horizontally a pin 36 carrying a roller 38 that bears upon the front face of the corresponding combined guide and sealing member. Secured to each of the side bars of the lower sash at a point considerably below the upper rail is a pivot 40 to which is attached a link 41, the other end of the latter being capable of swinging about a second pivot 42 fixed to the side member of the frame. The sashes are connected for supporting and counterbalancing purposes by a tape or chain 43, one end 44 of which is secured in any desired manner to the upper sash, the other end being continued downwardly along the side member of the lower sash to a point in proximity to the sill and there secured to a pin or other part 45 rigid with the sash.

25   *Operation.*

The parts normally occupy the position indicated in Fig. 1. When it is desired to secure ventilation, the lower sash is swung rearwardly on the pivots or pins 36 until the flanges 29-30 clear the flange 31 on the upper sash, after which the sashes may be shifted easily to form a slight opening at bottom and top. A much greater opening is, however, formed between the meeting rails, for the link 41 forces the upper part of the lower sash rapidly rearward. Further elevation of the lower sash will cause it to swing inwardly about the pins 36 into parallel relation to the upper sash, as indicated in Fig. 4. The joints 25-26 at the sides of the swinging sash and the joint 29-30-31 at the meeting rail effectually exclude air and moisture.

Because of the fact that the lower sash swings rearwardly, it is possible to employ the usual screens and awnings. It will be seen that the sections from which the window is made are of shapes that may readily be rolled, which is of importance, since the cost is reduced thereby, and also because it admits the use of heavier and stronger parts than can be obtained by pressing or stamping.

It is clear that many changes may be made in the details of construction without departing from the spirit of my invention. For example, the combined guide and sealing member may be of H-cross-section instead of U-shape, as shown. I do not, therefore, wish to be limited otherwise than as indicated by the subjoined claims.

I claim:—

1. A window comprising in combination a frame, an upper sash and a lower sash, means for guiding the upper sash for slid-

ing movement in a vertical plane, pivot means for the lower portion of the lower sash, means for guiding the pivot means for vertical movement, a link pivotally connected to the frame at a fixed point and to the upper portion of the lower sash for causing the sash to swing outwardly about the pivot means, and means for so connecting the sashes that each tends to counterbalance the other.

2. A window comprising in combination a frame, an upper sash and a lower sash, means for guiding the upper sash for sliding movement in a vertical plane, pivot means for the lower portion of the lower sash, means for guiding the pivot means for vertical movement, a link pivotally connected to the frame at a fixed point and to the upper portion of the lower sash for causing the sash to swing outwardly about the pivot means, and means for so connecting the sashes that each tends to counterbalance the other, said link being of such length as to cause the lower sash to swing backwardly into parallel relation to the upper sash upon a further movement thereof.

3. A window comprising in combination a frame, an upper sash and a lower sash, said sashes being of substantially the same length, means for guiding the upper sash for sliding movement in a vertical plane, pivot means for the lower portion of the lower sash, means for guiding the pivot means for vertical movement, means for so connecting the upper sash to the pivot means for the lower sash that the sashes tend to counterbalance each other, a link pivotally connected to the frame at a fixed point and to the upper portion of the lower sash, said link being of a length such that the upper end of the lower sash is first caused to swing outwardly about the pivot means as the window is opened and afterward caused to assume parallel relation to the first mentioned sash when the sashes reach the same level.

4. A window comprising in combination a frame, an upper sash, and a lower sash, means for guiding the upper sash for sliding movement in a vertical plane, pivot means for the lower portion of the lower sash, means for guiding the pivot means for vertical movement, a link having a fixed pivotal connection with the frame and with the upper portion of the lower sash for simultaneously forcing the upper portion of said sash to swing outwardly about the pivot means, means for so connecting the sashes that each tends to counterbalance the other, said upper sash and said lower sash each comprising meeting rails, a flange on one of the rails and a pair of spaced flanges on the other rail arranged to receive and embrace the first mentioned flange when the window is closed, said link causing the upper portion of the lower sash to swing inwardly.

about the pivot means as the sashes approach the limit of their closing movement, whereby the flange on the one rail is brought into alinement with the space between the flanges on the other rail to form a tight joint.

5. A window comprising in combination a frame, an upper sash, and a lower sash, means for guiding the upper sash for sliding movement in a vertical plane, pivot means for the lower portion of the lower sash, means for guiding the pivot means for vertical movement, a link having a fixed pivotal connection with the frame and with the upper portion of the lower sash for simultaneously forcing the upper portion of said sash to swing outwardly about the pivot means, means for so connecting the sashes that each tends to counterbalance the other, 10 said upper sash and said lower sash each 15

comprising meeting rails, a flange on the meeting rail of the upper sash, and a pair of spaced flanges on the meeting rail of the lower sash arranged to receive and embrace the first mentioned flange when the window 25 is closed, said link causing the upper portion of the lower sash to swing inwardly about the pivot means as the sashes approach the limit of their closing movement, whereby the flange on the one rail is brought into alinement with the space between the flanges on the other rail to form a tight joint.

10. In testimony whereof I sign this specification in the presence of two subscribing witnesses.

THOMAS H. KANE.
